AIR STRAINER

Clyde C. Farmer, Pittsburgh, Pa., assignor to
 The Westinghouse Air Brake Company, Wil-
 merding, Pa., a corporation of Pennsylvania

Application June 16, 1936, Serial No. 85,519

24 Claims. (Cl. 183—49)

This invention relates to fluid pressure systems and more particularly to means for cleansing fluid supplied to the system, the present application being in part a continuation of my co-pending application, Serial No. 758,779, filed December 22, 1934.

The desirability and advantages of cleaning air which is being supplied to a fluid pressure system are well known by those skilled in the fluid pressure art, but since there are so many different types of systems where air cleaners or filters are used, the present invention will, for illustrative purposes only, be described in connection with a railway fluid pressure brake system where it is especially desirable and advantageous to cleanse the air supplied thereto of foreign matter such as dirt and moisture.

In a railway fluid pressure brake system the several fluid pressure controlled valve devices, chambers, and conduits connecting the chambers and devices are charged with fluid under pressure by way of a brake pipe which forms a part of the system. The control of such valve devices is accomplished by varying the brake pipe pressure as is well known by those skilled in the fluid pressure brake art.

Fluid being supplied through the brake pipe of a fluid pressure brake system may contain particles of foreign matter so minute that it is difficult to prevent them from passing into the control valve devices, and as a result these particles accumulate on the working surfaces of the movable parts of the valve devices and may also accumulate in feed grooves or other communications of small flow area, either or both of which conditions may eventually cause sluggish action of the valve devices or in some cases result in complete failure of said devices. Further if the particles of foreign matter are of an abrasive nature they will cause excessive wear of the working parts of the valve devices and ultimately the failure thereof.

It has been ascertained under actual operating conditions that while the air cleaners or filters usually employed in fluid pressure brake systems do separate large particles of dirt from air being supplied to the system, they are not in every case so efficient in removing minute particles of dirt from the air stream, and it is these latter particles which, if not removed by the strainer, are liable to accumulate in the valve devices and seriously interfere with their operation as above pointed out.

The principal object of the invention is to provide an improved air cleaning and filtering means

for embodiment in a fluid pressure system and which is adapted to remove both large and minute particles of foreign matter from the air being supplied to the system thereby eliminating the possibility of the above mentioned faulty operation of control devices included in the system.

In my aforementioned copending application I have disclosed an air strainer device which is similar in some respects to the device of the present application but which comprises inner and outer concentrically arranged tubular retaining members which are formed of wire mesh and which have laterally extending lugs holding the straining material in place longitudinally of the device, each of said lugs being formed by the end loop of two adjacent longitudinal strands of the wire mesh which project beyond the outer annular strand.

In practice it has been found that if extreme care is not exercised in the bending of each of the lugs laterally to hold the straining material in place, the bend point in some of the lugs may not be on the outside of the annular end strand of the mesh as intended but rather on the opposite side, this latter condition being possible by distortion of the annular end strand which can easily occur due to the inherent pliability of the mesh. From this it will be seen that the lugs in some cases might extend more than one-half of the distance between the inner and outer retaining members so that when the strainer is secured in place in a casing the ends of the annular bosses on the casing and the securing nut instead of engaging the straining material as intended will engage these lugs and, as a result of this metal to metal contact, there may be small openings between the bosses and the lugs which will permit unwanted flow of uncleansed air from one side of the strainer to the other.

It has also been found in some cases that the bonds or connections between some of the longitudinal and annular strands of the wire mesh retaining members of the strainer device are not strong enough to withstand the torsional stresses transmitted thereto by the securing nut or plug when the nut is being screwed to its proper securing position, and as a result the retainers will be twisted by the action of the securing nut. The degree of such twisting may be such as to shorten the strainer device and may also cause the lugs, which hold the straining material in place, to straighten out. So far as the cleansing of the air stream is concerned, the efficiency of the strainer device is not impaired by such dis-

tortion as long as the strainer device is clamped in the casing, but when the device is removed from the casing for the purpose of cleaning it of foreign matter which it has collected, the filtering material, being inherently resilient, will expand and thereby protrude beyond the ends of the retaining members if the holding lugs have been unintentionally straightened out as just described.

10 If the retaining members of the device have been shortened due to the twisting of the wire mesh as above described, the strainer will be unfit for further service for the reason that the proper engagement between the straining material and the bosses of the casing and securing nut cannot be obtained, due to the movement of the securing nut to its securing position being limited.

20 A strainer device of the type disclosed in the present application and in my copending application before referred to is adapted to be cleaned of foreign matter, which it has collected, by a method in which one of the steps consists in rotating the device axially at a very high speed 25 and it has been found that the expansion of the straining material, due to centrifugal force, causes the lugs at the ends of the device to straighten out, with the result that the straining material will protrude beyond the ends of the 30 retaining members and in some cases may be forced out from between the retaining members, all of which is of course very objectionable.

35 To provide the maximum rigidity to the strainer device, the wires of the mesh are made of steel, but since steel will not withstand repeated bending without breaking, it will be apparent that if the lugs of the retaining members are straightened out after having once been bent laterally they are liable to break off in attempting 40 to bend them again to their holding position, thus when the lugs are unintentionally straightened out by the twisting of the retainers or by the action of the straining material while the strainer device is being rotated in a cleaning 45 machine, the strainer device is liable to be rendered unfit for service by the breakage of the lugs in attempting to again bend them to their holding position.

50 Another object of the invention is to provide a strainer device comprising inner and outer concentrically arranged foraminous hollow retaining members which are so constructed as to be free of all of the above mentioned objectionable 55 features. According to this object each retaining member is made from a single piece of material such, for instance, as a section of seamless tubing of brass or any other suitable material or a flat metal plate rolled or bent to hollow form and having the meeting edges of the plate soldered or otherwise secured together.

55 In practice it was ascertained that the wire mesh best suited for making the retaining members of a strainer device to be employed in fluid pressure brake equipments, where the strainer is limited both in length and diameter and where a certain amount of cleaning material must be packed between the retaining members to insure the proper cleaning of air which passes therethrough, is one which is woven of wire strands 60 of small diameter and number about nine per inch. If the mesh were woven of wire of greater diameter either the diameter of the strainer would be increased or the space into which the straining material is packed would be reduced 65 in width either of which conditions is objectionable.

70 If the mesh were woven of wire of smaller diameter the desired rigidity of the strainer would not be obtained.

75 With the above in view it will be apparent that another advantage to be derived from making each retaining member of the strainer device of a unitary construction instead of woven wire mesh is that the openings through which the air is adapted to pass may be reduced in number and so increased in size that the total flow area of the openings will be considerably greater than that of the openings of the wire mesh heretofore employed, thus retaining members made in accordance with the invention will offer less resistance to the flow of air than will the wire 10 mesh members.

15 The wire mesh from which the retaining members have heretofore been made has sixty-four openings per square inch whereas my improved retaining members have only sixteen per square 20 inch. From this it will be understood that in the improved retaining members the bridging portions between the openings may be made wider than the diameter of the strands of the wire mesh and yet not impede or resist the flow of 25 air through the strainer as much as does the strands of the wire mesh, all of which contributes to the increased efficiency and strength of the strainer device as a whole.

30 Other objects and advantages will appear in the following more detailed description of the invention.

35 As shown in the accompanying drawings, Fig. 1 is a side elevational view of a strainer device embodying the invention and illustrating retaining members which are each made from seamless tubing; Fig. 2 is an end elevational view of the same; Fig. 3 is a fragmentary vertical sectional view of a portion of a brake controlling valve device with the strainer device mounted 40 therein, said device being shown in longitudinal section and Fig. 4 is a sectional view similar to Fig. 3 but made on a reduced scale and showing several of the working parts of the brake controlling valve device and showing the strainer device in elevation. Fig. 5 is a fragmentary side elevational view of the strainer device illustrating one way of constructing each of the tubular retaining members from a single flat plate; Fig. 6 is a fragmentary end elevational view of the 50 same; Figs. 7 and 8 illustrate another way of constructing the tubular retaining members from a single flat plate, Fig. 7 being a fragmentary longitudinal sectional view of the strainer device and Fig. 8 being a cross-sectional view taken 55 on the line 8-8 of Fig. 7. Figs. 9 and 10 are cross-sectional views similar to Fig. 8 but each illustrating still another way of constructing each of the retaining members from a single flat plate. Fig. 11 is an end elevational view of a 60 strainer embodying the invention and illustrating another form of the retaining lugs at the ends of the retaining members. Figs. 12, 13, 14 and 15 illustrate still another form of the retaining lugs and the method of forming them, 65 Fig. 12 being a fragmentary plan view of the plate preparatory to forming a retaining member; Fig. 13 is a view similar to Fig. 12 but illustrating how a portion of the plate is folded on itself to form the retaining lugs; Fig. 14 is a 70 fragmentary longitudinal sectional view of a strainer and illustrating the lugs bent to their retaining position and Fig. 15 is a fragmentary end elevational view illustrating the lugs in their retaining position. Fig. 16 is a fragmentary sec- 75

tional view illustrating a modified form of the end portion of the strainer and also illustrating how it functions when secured in place in a casing.

As shown in the drawings, the air strainer or filter device is preferably of cylindrical form and comprises inner and outer foraminated tubular members 1 and 2, respectively, which are preferably of equal length and are arranged concentrically with respect to each other, the member 2 being made of greater diameter than the member 1 and surrounding or encircling the member 1 for its full length, so as to provide space between the members for the reception of air straining material.

The retaining members are each provided at each end with a relatively short longitudinally extending imperforate annular web 4 and extending between and integrally connected to the inner ends of the webs 4 is the foraminated portion 5 of the member.

Surrounding or encircling the retaining member 1 is a sleeve or covering 6 of porous material, such for instance as relatively thin felt or any other material which will not offer any substantial resistance to the flow of air therethrough and yet will separate minute particles of foreign matter, such as dust, from the air as it passes therethrough.

The space between the covering 6 and the inner surface of the outer retaining member 2 is packed with a suitable straining material 7, such as curled hair, which is confined at each end of the strainer device by means of a relatively thick flexible annular washer 8 which is preferably made of felt and which fits snugly in the space between the covering 6 and the inner surface of the retaining member 2. The end of the covering 6 extends through the central opening in the washer 8 and is flared outwardly as indicated by the reference character 9 into overlapping relation with the outer surface of the washer.

It will be understood that the covering 6 besides serving to remove minute particles of foreign matter from air passing therethrough also serves to isolate the curled hair straining material from the core of the strainer device so that the possibility of portions of the straining material passing into the valve devices is entirely eliminated.

At each end of the strainer device the washer 8 and flared portion 9 of the covering 6 are retained in position between the members 1 and 2 by means of short lugs 10 and 11 which are bent laterally of the space between the members, the lugs 10 when so bent extending outwardly from the annular web of the member 1 and the lugs 11 extending inwardly from the annular web of the member 2. As shown in the drawings these lugs are preferably integral with the outer ends 60 of the webs 4 of the members 1 and 2.

The length of the lugs 10 and 11 is less than one-half of the width of the space between the members 1 and 2 so that there is a clear annular space between the ends of these lugs in which annular bosses are adapted to engage the outer faces of the washers 8 without a metal to metal contact being made between the bosses and the lugs, all of which will hereinafter more fully appear.

As shown in Figs. 1 to 4, inclusive, the tubular retaining members 1 and 2 may each be made from a relatively short piece of seamless tubing which may be of brass or any other non-rusting material or as shown in Figs. 5 to 10 inclusive and 75 12 to 15 inclusive may be made from a flat plate

which is bent to tubular form and which has its ends soldered, welded, interlocked or otherwise secured together.

As shown in Figs. 5 and 6 each of the end edges of the plate from which each of the retaining members is formed comprises an imperforate web 12 to which the longitudinally extending bridge pieces between the openings of the foraminated portion of the plate are integrally connected. When the plate is bent to its desired form the end webs 12 overlap each other and in this relationship are soldered or welded together. It will be noted that one end web of the plate from which the inner retaining member 1 is formed is offset outwardly a distance equal to the thickness 15 of the plate and that one web of the plate from which the retaining member 2 is formed is similarly offset in the opposite direction, so that when the end webs of the plates are secured together and the members incorporated in a strainer device, the inner and outer faces of the device will each be of plain circular form, that is to say will be free of projections.

As shown in Figs. 7 and 8 the end webs 12 of the plates may be provided with folds 25 which are 25 interlocked together and which are pressed into close engagement with each other to securely fasten the webs together against accidental separation or movement relative to each other. The folds in the webs 12 are so arranged that when 30 the inner and outer retaining members 1 and 2 are incorporated in a strainer device they will extend into the space between the members so that inner and outer faces of the strainer device will each be of plain circular form as is the case 35 in the strainer device shown in Figs. 5 and 6. With this form of joint, the interlocking folds are preferably terminated short of the outer ends of the retaining members as shown in Fig. 7, thus eliminating the possibility of the folds distorting 40 the inner and outer edges of the washer, which might otherwise occur and provide spaces through which air might flow without being properly cleaned.

As shown in Fig. 9, the outer ends of the end 45 webs 12 of the plate may be arranged in abutting relationship with each other and secured together by means of a narrow plate 13 soldered or welded to each web.

As shown in Fig. 10 the end webs 12 may be secured together in overlapping relation without offsetting one of them. With this form of joint the outer surface of the outer retaining member will not of course be in the form of a true circle but where the strainer does not have to fit snugly 55 in a casing this will not be objectionable.

As shown in Fig. 11 the lugs 10 and 11 may be made wider at their bases than at their ends instead of being of even width for their full length as shown in Figs. 2 and 6.

In some cases the retaining members 1 and 2 of the strainer device may be made of thinner material than that required in a strainer device for use in fluid pressure brake equipment but when thinner material is used it is necessary to make 65 the lugs at the ends of the members stiff enough to withstand, without bending, the outwardly directed pressure of the straining material when the strainer device is being cleaned in the cleaning device hereinbefore mentioned, and in Figs. 12, 13 and 14 one way of doing this is illustrated.

As shown in Fig. 12 the webs 4 at opposite sides of the plate from which a retaining member is to be formed, instead of having spaced lugs formed at their outer edges, are extended in 75

width and provided with openings 27. To form the lugs the plate is folded back upon itself as shown in Fig. 13, the fold being on a line which passes through the openings 27 midway between their ends. From this it will be seen that the lugs will be spaced apart as in the retaining members hereinbefore described and will be of two thicknesses of metal and will therefore have the required stiffness to withstand the action of the 10 straining material when the strainer device is being cleaned in a cleaning device.

After the lugs have been formed as just described, the plate is rolled into tubular form and the meeting ends thereof joined together in any 15 one of the ways hereinbefore described.

In Fig. 16 a modified form of strainer device is shown which differs from the device hereinbefore described in that the ends of the covering 6 are flared outwardly far enough to cover the 20 ends of the curled hair 7 and in that the washers 8 are omitted.

The preferred method of assembling my improved strainer device is to first bend the lugs 10 and 11 at one end of the retaining members 1 25 and 2, respectively, to their retaining position to then flare one end of the covering 6 outwardly, then with the retaining members standing on the lugs 10 and 11 in their proper spaced position with relation to each other insert one of the washers 30 8 between the members and into engagement with the flared portion of the covering 6 and lugs 10 and 11, to then pack the straining material between the covering 6, washer 8 and retaining member 2, to then insert the other washer 8 between 35 the members 1 and 2, to then flare the other end of the covering 6 outwardly over the last mentioned washer and to finally bend the lugs 10 and 11 at the other end of the retaining members to their retaining position.

40 From this it will be understood that if desired the lugs 10 and 11 which are first bent to the position in which they are adapted to maintain the packing material in place may be substituted by a laterally extending flange which may be integral with the members. In case the members are made of seamless tubing these flanges may be spun on the members.

Having thus described my improved strainer device and the preferred method of making it 50 the mounting of the strainer in a supporting casting and its functioning when mounted will now be described.

In Fig. 3 of the drawings, the strainer device is shown, for illustrative purposes only, embodied 55 in a fluid pressure brake controlling valve device which comprises a casing 14 having a fluid conducting passage 15 which may be considered as leading from the usual brake pipe (not shown) and also having a fluid conducting passage 16 60 which leads to the emergency piston chamber 17 of the valve device (see Fig. 4). The passages 15 and 16 are both connected to a chamber 18 containing my improved strainer device which, during the assembly of the valve device, is inserted 65 through an open threaded end of the chamber 18 and which is secured in said chamber by means of a screw plug 19 which has screw-threaded connection with the casing within the open end of the chamber, said plug having a passage 20 leading from the chamber 18 to the triple valve piston chamber 21 of the valve device.

The inner end of the plug 19 is provided with an annular rib 22 which is preferably of V-shape in cross section and which engages the washer 8 75 at one end of the strainer device within the clear

space between the ends of the adjacent lugs 10 and 11 and flexes the washer inwardly, as shown in Fig. 3, as the plug is turned to its normal securing position. At the same time a similar rib 23 carried by the rear wall of the chamber 18 5 engages the other washer 8 in the clear space between the ends of the adjacent lugs 10 and 11 and flexes this washer inwardly. The washers 8 being made of such material as felt, the ribs 22 and 23 become partially embedded in the washers a sufficient distance that there is no liability of there being any free open space between the strainer device and the casing to permit leakage of uncleansed air from passage 15 to passages 16 10 and 20 and thereby to piston chambers 17 and 21. 15

The packed curled hair, due to its inherent resiliency and also due to the flexing of the washers as just described, will closely engage the washers 8 and the ends of the strainer so that there is no possibility of the leakage of uncleansed 20 air through the strainer at points adjacent the washers.

In charging a fluid pressure brake equipment initially or to release the brakes, fluid under pressure supplied to the brake pipe flows through 25 passage 15 to the chamber 18 and from thence flows through the strainer device to the passages 16 and 20 and consequently to the piston chambers 17 and 21. As the air is passing through the strainer device, the curled hair 7 catches the 30 large particles of foreign matter and the felt covering 6 catches the particles which are too minute to be caught by the curled hair. From this it will be apparent that a thorough cleaning of the air passing from the supply passage to 35 the working parts of the valve device is insured.

As shown in Fig. 3 there is considerable clearance between the left hand end of the strainer device and the casing and also between the right hand end of the device and plug 19 which serves 40 to prevent the strainer device from being clamped in metal to metal contact with the casing and plug when due to slight inaccuracies in the manufacture of the casing and the plug the distance between the inner end of the chamber 17 45 and the plug is less than that intended, thus insuring against the possibility of the distortion of the retaining members by the action of the plug. It will here be understood that the ribs 22 and 23 by reason of their engagement with the 50 washers 8 and the outward pressure of the curled hair 7 on the washers, the strainer device is rigidly held in place in the casing against unwanted movement in any direction.

When the brake pipe pressure is reduced to 55 effect an application of the brakes, the consequent flow of fluid under pressure from the piston chambers 17 and 21 and through the strainer device will tend to detach and carry away from the strainer any foreign matter which may have 60 accumulated therein, thus the strainer is rendered self-cleaning to such an extent that the strainer may be used over a long period of time without danger of becoming clogged. This self-cleaning action is most effective when an emergency application is initiated for the reason that the brake pipe pressure and consequently the pressures of the piston chambers 17 and 21 of the brake controlling valve device is reduced at a rapid rate and to substantially atmospheric 65 pressure. The flow of fluid from the chambers 17 and 21 in effecting an emergency application of the brakes is through the passages 16 and 20, strainer device, chamber 18 and a passage 24 70 which leads to the usual vent valve device (not 75

shown) which establishes communication from the passage 24 to the atmosphere. This passage 24 is relatively short so that the foreign matter blown from the strainer will be carried to the atmosphere with the fluid being released from the piston chambers as well as from the brake pipe.

While several illustrative embodiments of the invention have been described in detail, it is not my intention to limit its scope to these embodiments or otherwise than by the terms of the appended claims.

Having now described my invention, what I claim as new and desire to secure by Letters 15 Patent, is:

1. In a strainer, in combination, a hollow foraminous core having outwardly directed lugs at its ends, a foraminous body portion surrounding said core and spaced therefrom and having 20 inwardly directed lugs at its ends, there being clear space between the ends of the lugs of said core and the ends of the lugs of said body portion, a mass of straining material packed in the space between said core and body portion, and 25 a ring of flexible material at each end of the strainer interposed between said core and body portion and retained in position by said lugs.

2. In a strainer, in combination, a hollow foraminous core having outwardly directed lugs 30 at its ends, a sleeve of pervious material surrounding said core, a foraminous body portion surrounding said sleeve and spaced therefrom and having inwardly directed lugs at its ends, the ends of the lugs of said core and the ends 35 of the lugs on said body portion being spaced apart laterally of said core and body portion, a mass of straining material packed in the space between said sleeve and body portion, and a ring of flexible material at each end of the strainer 40 interposed between said sleeve and body portion and retained in position by said lugs.

3. In a strainer, in combination, a hollow foraminous core having outwardly directed lugs at its ends, a sleeve of pervious material surrounding said core and having outwardly directed 45 flanges at its ends, a foraminous body portion surrounding said sleeve and spaced therefrom and having inwardly directed lugs at its ends, and a mass of straining material packed in the space between said sleeve and said body portion, said lugs acting to retain the respective flanges 50 in position.

4. The combination with a fluid pressure operated device, of a strainer for removing foreign 55 matter from fluid supplied to said device, said device comprising a casing having a bore through which fluid under pressure is adapted to be supplied to said device, said strainer comprising a hollow foraminous core, a foraminous body portion surrounding said core and spaced therefrom, a mass of straining material packed in the space 60 between said core and body portion, a ring of flexible material at each end of the strainer interposed between said bore and body portion, a retaining element adapted to be received in 65 said bore to position and retain said strainer, means in said bore adapted to engage one of said rings upon application of said retaining element, and means associated with said retaining element adapted to engage the other of said rings, each of said means cooperating with the 70 respective ring to effect an air-tight seal against leakage of fluid under pressure past the ends of said strainer and thereby insure the passage of fluid through said strainer.

5. The combination with a fluid pressure operated device, of a strainer for removing foreign matter from fluid supplied to said device, said device comprising a casing having a bore through which fluid under pressure is adapted to be supplied to said device, said strainer comprising a hollow foraminous core, a sleeve of pervious material surrounding said core, a foraminous body portion surrounding said sleeve and spaced therefrom, a mass of straining material packed in the space 10 between said sleeve and body portion, a ring of flexible material at each end of the strainer interposed between said core and body portion, a retaining element adapted to be received in said bore to position and retain said strainer, means in said bore adapted to engage one of said rings and flex same inwardly upon application of said retaining element, and means 15 associated with said retaining element adapted to engage and flex inwardly the other of said rings, each of said means cooperating with the respective ring to effect an air-tight seal against leakage of fluid past the end of the strainer, the flexing of said rings acting to compress the straining material therebetween to further insure the passage of fluid through said strainer.

6. The combination with a fluid pressure operated device, of a strainer for removing foreign matter from fluid supplied to said device, said device comprising a casing having a bore through which fluid under pressure is adapted to be supplied to said device, said strainer comprising a hollow foraminous core, having outwardly directed lugs at its ends, a sleeve of pervious material surrounding said core, a foraminous body portion surrounding said sleeve and spaced therefrom and having inwardly directed lugs at its ends, the lugs on said body portion being spaced from the lugs on said core, a mass of straining material packed in the space between said sleeve and body portion, a ring of flexible material at each end of the strainer interposed between said sleeve and body portion, a retaining element adapted to be received in said bore to position and retain said strainer, means in said bore adapted to engage one of said rings in the space between the lugs on said core and on said body portion upon application of said retaining element, and means associated with said retaining element adapted to engage the other of said rings in the space between the lugs on said core and body portion, each of said means cooperating with the respective ring to effect an air-tight seal against leakage of fluid under pressure past the ends of the strainer and thereby insure the passage of fluid through the strainer.

7. The combination with a fluid pressure operated device, of a strainer for removing foreign matter from fluid supplied to said device, said device comprising a casing having a bore through which fluid under pressure is adapted to be supplied to said device, said strainer comprising a hollow foraminous core, having outwardly directed lugs at its ends, a sleeve of pervious material surrounding said core and having outwardly directed flexible flanges at its ends, a foraminous body portion surrounding said sleeve and spaced therefrom and having inwardly directed lugs at its ends, the lugs on said body portion being spaced from the lugs on said core, a mass of straining material packed in the space between said sleeve and body portion, a retaining element adapted to be received in said bore to position and retain said strainer, means in said bore adapted to engage and flex inwardly

one of said flanges upon application of said retaining element, and means associated with said retaining element adapted to engage and flex inwardly the other of said flanges, each of said means cooperating with the respective flange to effect an air-tight seal against leakage of fluid under pressure past the end of the strainer, the flexing of said flanges acting to compress the straining material therebetween to further insure 5 the passage of fluid through said strainer.

10. In a strainer device, in combination, spaced tubular members arranged one within the other, each of said members comprising imperforate longitudinally extending end webs and a foraminous portion extending between said end webs and connected thereto, straining material interposed between said members, and lugs integral with said end webs for maintaining said straining material in position with respect to said 15 members, said lugs extending laterally from said webs and being deflected longitudinally of the members in directions toward said foraminous portions at an acute angle to the web.

10. In a strainer device, in combination, spaced 20 tubular members arranged one within the other, each of said members comprising imperforate longitudinally extending end webs and a foraminous portion extending between said end webs and connected thereto, straining material interposed between said members, and lugs integral with said end webs and extending laterally into the space between said members for maintaining said straining material within the outer end edges of said end webs, each of said lugs being of less 25 than one-half of the width of the space between said members.

10. In a strainer device, in combination, spaced 30 tubular members arranged one within the other, each of said members comprising imperforate longitudinally extending end webs and a foraminous portion extending between said end webs and connected thereto, straining material interposed between said members, and spaced lugs extending outwardly from the outer end of each 35 of said end webs and bent laterally to a position for maintaining said straining material confined within the outer end edges of said end webs, the ends of the lugs at each end of one member being spaced away from the ends of the lugs at the same end of the other member.

10. In a strainer device, in combination, spaced 40 tubular members arranged one within the other, each of said members comprising imperforate longitudinally extending end webs and a foraminous portion extending between said end webs and connected thereto, straining material interposed between said members, and spaced lugs extending laterally from the outer end of each 45 of said end webs adapted to maintain said straining material within the space between said members, said lugs being deflected longitudinally of the members in directions toward the foraminous portions for maintaining the straining material within the outer end edges of the end webs.

10. In an air strainer, a casing element comprising a tubular member having annular end webs, a foraminous portion extending between and integrally connected to said webs, and straining material retaining means integral with said webs and extending laterally thereof and being deflected longitudinally of the member in directions toward the foraminous portions at an acute angle thereto.

10. In a strainer device, in combination, spaced 50 tubular casing elements arranged one within the

other and each comprising a single piece of material having annular end webs, a foraminous portion integrally connected to said webs, straining material between said elements, and means carried by said webs and extending laterally thereof and inwardly in the direction of the foraminous portions of the members adapted to retain the straining material between said elements.

14. In a strainer device, in combination, spaced 55 tubular members arranged one within the other and each comprising annular end webs and a tubular foraminous portion extending between and integrally connecting said end webs, straining material in the space between said members, an annular washer at each end of the strainer device interposed between said members in the plane of said webs at the corresponding end of the strainer and engaging said straining material, and means for retaining the washers and thereby the straining material between said members, said washers being resilient and pervious to air.

15. In a strainer device, in combination, spaced 60 tubular members arranged one within the other and each comprising annular end webs and a tubular foraminous portion extending between and integrally connecting said end webs, straining material in the space between said members, and extending into the plane of the annular webs at each end of the strainer device, an annular washer interposed between said members at each end of the strainer for retaining the straining material between said members and means for retaining the annular washers between said members, said annular washers being resilient and pervious to air.

16. In an air strainer, a casing element comprising a tube having spaced annular end webs, a foraminous portion integrally connecting said webs, and spaced straining material retaining lugs at each end of the tube extending in a direction across the end of the tube and deflected longitudinally of the tube in directions toward the foraminous portion.

17. An air strainer casing element comprising a tubular member made of a flat plate bent to tubular form and having its ends interlocked to form a rigid joint therebetween, said member comprising spaced annular end webs and a foraminous portion extending between and integrally connecting said end webs, said joint terminating short of the outer ends of said webs to provide a plain inner surface for engagement by an annular straining material retaining washer.

18. In an air strainer, a retaining wall member comprising a tubular section having imperforate end webs and a foraminous connecting portion and straining material retaining lugs projecting laterally from said webs, said lugs being deflected longitudinally of the member in directions toward said foraminous connecting portion.

19. In a strainer device, in combination, spaced 65 tubular members arranged one within the other and each comprising annular end webs and a tubular foraminous portion extending between and integrally connecting said end webs, straining material in the space between said members, an annular washer at each end of the strainer device interposed between said members in the 70 plane of said webs at the corresponding end of the strainer and engaging said straining material, a sleeve of pervious material interposed between one of said tubular members and said straining material and covering the foraminous 75

the member and being flared over each washer, and means carried by said members for retaining the washers and thereby the straining material between said members, the retaining means carried by the member having the foramen covered by the sleeve clamping the flared portions of the sleeve to said washers.

20. In a strainer device, in combination, spaced tubular members arranged one within the other 10 and each comprising annular end webs and a tubular foraminated portion extending between and integrally connecting said end webs, straining material in the space between said members, an annular washer at each end of the strainer 15 device interposed between said members in the plane of said webs at the corresponding end of the strainer and engaging said straining material, a sleeve of previous material surrounding the inner one of said tubular members and covering the foramen thereof and being flared at its ends over the inner edges of said washers, and means carried by said members for retaining the washers and thereby the straining material between said members, the retaining means carried 25 by the inner member retaining the flared portions of the sleeve in overlapping relationship with said washers.

21. In a strainer, in combination, a hollow foraminous core having outwardly directed lugs at 30 its ends, a foraminous body portion surrounding said core and spaced therefrom and having inwardly directed lugs at its ends, there being clear space between the ends of the lugs of said core and the ends of the lugs of said body portion, straining material in the space between said core and body portion and two rings of flexible material interposed between said core and body portion and arranged one at each end of the strainer 35 and covering the ends of the straining material, 40 said rings being retained in position by said lugs.

22. In a strainer, in combination, a hollow foraminous core having outwardly directed lugs at its ends, a foraminous body portion surrounding said core and spaced therefrom and having inwardly directed lugs at its ends, there being clear 5 space between the ends of the lugs of said core and the ends of the lugs of said body portion, straining material in the space between said core and body portion and two rings of flexible material 10 interposed between said core and body portion and arranged one at each end of the strainer and covering the ends of the straining material, said rings being retained in position by said lugs and retaining the straining material positioned against movement in directions longitudinally of 15 said core and body portion.

23. In an air strainer, a casing element comprising a seamless tube having spaced annular end webs, a foraminated portion integrally connecting said webs, and spaced straining material retaining lugs at each end of the tube extending in a direction across the end of the tube and deflected longitudinally of the tube in directions 20 toward the foraminated portion.

24. In a strainer device, in combination, 25 spaced seamless tubular members arranged one within the other, each of said members comprising imperforate longitudinally extending end webs and a foraminous portion extending between said end webs and connected thereto, 30 straining material interposed between said members, and lugs integral with said end webs for maintaining said straining material in position with respect to said members, said lugs extending laterally from said webs and being deflected 35 longitudinally of the members in directions toward said foraminous portions at an acute angle to the web.

CLYDE C. FARMER.
